SEDGWICK A. SUTTON, OF DIXON, ILLINOIS, ASSIGNOR TO HIMSELF, W. UHL, AND LYSANDER FLAGG.

Letters Patent No. 80,679, dated August 4, 1868.

IMPROVEMENT IN FILE-CUTTING MACHINES.

The Schedule referred to in these Letters Patent and making part of the same.

TO ALL WHOM IT MAY CONCERN:

Be it known that I, SEDGWICK A. SUTTON, of Dixon, in the county of Lee, and State of Illinois, have made and invented new and useful Improvements in File-Cutting Machinery; and I do hereby declare that the following is a full, clear, and exact description thereof, which will enable others skilled in the art to make and use the same, reference being had to the accompanying drawings, forming part of this specification.

This invention relates to certain new and useful improvements in file-cutting machinery, and is more especially designed to be applied to a file-cutting machine, for which Letters Patent were granted to Edward Bucklin, bearing date February 27, 1866.

The present invention relates—

First, to an improvement in the hammer-shaft, as hereinafter fully shown and described, whereby the teeth are cut more perfectly than hitherto, and the chisel, in its ascent, prevented from cutting off a tooth made by a previous cut; a contingency of not unfrequent occurrence in the operation of other machines.

Secondly, this invention relates to an improved pressure-roller, the manner of applying it to the machine, &c., whereby it may always be adjusted at a proper distance from the chisel; and

Thirdly, this invention relates to an improvement in the screw-feed, the half nut pertaining to the same, whereby all play or backlash is avoided.

In the accompanying drawings—

Figure 1 is a side view of that portion of my invention which relates to the hammer-shaft and pressure-roller.

Figure 2 is a front view of the same.

Figure 3, a plan or top view of the same.

Figures 4 and 5, views pertaining to the improvement which relates to the screw-feed.

Similar letters of reference indicate corresponding parts.

A represents a face-plate, which is bolted to the framing of the machine, and B is a guide-plate, which is secured by a pivot-bolt, a, to the face-plate A, said plate being allowed to work on bolt a, and retained or steadied in position or movement by a screw, b, which passes through a curved slot in A, and into the rear side of B.

Within the guide-plate B there is fitted a slide, C, said plate being provided with a dove-tail groove to receive the slide, and the latter having dove-tail sides, by which the slide is retained in the plate, (see fig. 3.) The lower end of the slide C has a socket, D, projecting horizontally from its front side, and in this socket a slide, E, is fitted and secured by a set-screw, e. In the outer end of this slide there is a roller, F, having a convex periphery, as shown in figs. 2 and 3.

The rear of the face-plate A has two arms, d d, extending longitudinally from it, and in the outer part of these arms are the bearings of the hammer-shaft G.

This hammer-shaft is of curved or bent form, as shown clearly in fig. 1; and the object of the bends is to bring the journals e e about in a horizontal plane with the chisel H when the latter is in contact with the file-blank, (see fig. 1.) By this arrangement, the chisel is prevented from cutting off a tooth made by a preceding cut, a contingency which not unfrequently occurs when the journals e e are much higher than the face of the file-blank, owing to the circle described by the chisel throwing or rolling the tooth back; so much so, that when the chisel descends to make a cut for a succeeding tooth, it is liable to come in contact with the edge of the tooth made by the preceding cut, and completely destroy it, and spoil the file. This difficulty is fully obviated by my improvement.

The roller F is a pressure-roller simply, and, owing to its connection with the swivel on pivoted plate B, is allowed to conform to the position of the file-blank, shown in red in fig. 1, on which it bears, and, by adjusting the slide E, the roller F may always be kept at a proper point in relation to the chisel H.

The pressure-roller is made to bear upon the file-blank by means of a loaded lever, I, the fulcrum-pin f of which passes into a standard, J, pivoted at its lower end to the face-plate A, as shown at g, so as to be adjustable, the lever I having an oblong slot, h, made in it, through which a screw, f', passes into the slide C.

By adjusting the standard J, and thereby moving the lever I, the efficiency of the latter may be increased or diminished, and the roller F made to bear with a greater or less degree of pressure on the file-blank, as required.

K represents a clamp, composed of two parts or jaws, *j j'*, connected by a joint, *h*, at their lower ends. The upper parts of these jaws, at their face sides, are hollowed out in semicircular form, the cavity of the jaw *j* being smooth, and *j'* having a screw-thread, *l*, like a nut, to engage with the screw of the feed-mechanism, when the two jaws are in contact. The two jaws are held in contact by a spring-catch, L, at their upper ends.

M is a lever, the lower end of which is forked and secured to the jaw *j'* by a fulcrum-pin, *m*, the lower ends of the prongs of the forks having a rod or pin, *n*, passing through them, which pin passes between the two jaws *j j'*.

This lever M also has a pin, *o*, attached, which passes into a recess in the top of the jaw *j'*, and has a shoulder on it to act against the edge of the catch L, and disengage the same from the jaw *j'* when the lever is drawn back.

Having thus described my invention, I claim as new, and desire to secure by Letters Patent—

1. The combination and arrangement of the pivoted guide-plate B, slides C and E, and the convex pressure-roller F, substantially as and for the purpose specified.

2. The loaded lever I, arranged or applied substantially as shown, with the standard J and oblong slot *h*, in combination with the slides C E and convex pressure-roller F, substantially as and for the purpose set forth.

3. The clamp K, composed of the jaws *j j'*, lever M, provided with the pins *n o*, and the catch L, applied to the clamp, and all arranged to operate in the manner substantially as and for the purpose specified.
